WET SPINNING APPARATUS

William H. Bradshaw, New Rochelle, N. Y., assignor to Celanese Corporation of America, New York, N. Y., a corporation of Delaware

Application May 16, 1951, Serial No. 226,593

5 Claims. (Cl. 18—8)

This invention relates to the production of viscose rayon filamentary materials and relates more particularly to a novel process and apparatus for the production of viscose rayon filamentary materials in a continuous manner.

An important object of this invention is to provide a novel process and apparatus for the production of viscose rayon filamentary materials in a continuous manner which will be especially efficient in operation and simple in construction.

Other objects of this invention, together with certain details of construction and combinations of parts, will be apparent from the following detailed description and claims.

In the production of viscose rayon filamentary materials, particularly viscose rayon fibers of staple length, it is necessary to subject said filamentary materials to a series of successive treatments under closely controlled conditions to obtain products having desirable physical properties. Advantageously, to minimize the expense involved in producing the viscose rayon filamentary materials, the successive treatments should be carried out automatically and with a minimum of manual labor.

According to the present invention, there is provided a novel process and apparatus for the production of viscose rayon filamentary materials which will fulfill the foregoing requirements, the apparatus being divided into four sections: a spinning section, a stretching section, a cooling section, and a cutting and opening section, through which sections the viscose rayon filamentary materials pass in succession. The present application relates specifically to the spinning section of the apparatus. In the spinning section, a viscose composition is pumped through a spinning jet, in the form of a strand containing up to 5000, or more, filaments into a coagulating medium which initiates the setting of the filaments. The strand and the coagulating medium are then caused to flow in the same direction through a generally U-shaped spinning tube wherein the setting of the filaments continues. As the strand emerges from the spinning tube, it is combined with the strands from one or more jets into a tow and is passed around a godet wheel which determines the speed of the tow and also provides a resistance against which the tow can be stretched by a drum over which it passes later on.

The term "filamentary materials" is employed herein to include filaments of indefinite length as well as fibers of staple length.

A preferred embodiment of the apparatus of this invention is shown in the accompanying drawings wherein:

Fig. 1 is a cross-sectional view of the apparatus, taken on an enlarged scale along the line 1—1 in Fig. 2, in the direction of the arrows,

Fig. 2 is a front elevational view, with portions broken away, of the apparatus,

Fig. 3 is a cross-sectional view, taken along the line 3—3 in Fig. 1, in the direction of the arrows, and

Fig. 4 is a detail perspective view, on an enlarged scale

2

and with parts broken away, of the inlet funnel for guiding the tow into the spinning tube.

Spinning section

Referring now to the drawings, and more particularly to Figs. 1 and 2 thereof, the reference numeral 21 designates conduits through which a suitably ripened viscose composition is pumped by any suitable means (not shown) through a goose-neck, indicated generally by reference numeral 22, to a spinning jet, indicated generally by reference numeral 23. The spinning jet 23 is positioned in a trough 24 into which a stream of a suitable coagulating medium is pumped continuously through a conduit 25. The viscose composition emerges from the spinning jet 23 into the coagulating medium in the form of a strand 26 containing up to about 5000, or more, individual filaments which are caused to set by the action thereon of the coagulating medium. The strand 26 together with the coagulating medium then pass through suitable guide means, such as an inlet funnel 27, into a generally U-shaped spinning tube 28, composed of a vertically disposed conduit 29, a horizontally disposed connecting conduit 31 and a vertically disposed conduit 32, all joined together with elbows 33. Grooved guides 34 are provided in each of the elbows 33 to direct the strand 26 through the tube 28 and are positioned so as to guide the strand 26 along the center lines of the conduits 29, 31 and 32 thereby minimizing the development of turbulence in said conduits. The shape and positioning of the grooved guides 34 also tend to cause the flow of the coagulating medium to hold the strand 26 away from the guide thus reducing greatly the tension developed by the friction of the strand 26 against the said guide.

A constant head of coagulating medium is maintained on the inlet funnel 27 by pumping an excess of said medium into the trough 24 and permitting said excess to overflow into a channel 35 connected to a trough 36 which extends parallel to and is positioned adjacent the trough 24. The strand 26 and the coagulating medium emerge from the spinning tube 28 into the trough 36 through suitable guide means, such as an outlet funnel 37, whose cross-sectional area increases toward the discharge end thereof whereby the velocity of the coagulating medium will decrease immediately prior to its discharge from said outlet funnel. As a result, the coagulating medium will show little or no tendency to spurt from said outlet funnel as a column enclosing the tow 26, although a certain amount of the coagulating medium will, of course, be held within the interstices between the filaments of said strand. The coagulating medium which overflows into the channel 35 and which flows through the outlet funnel 37 is drained from the trough 36 through a discharge conduit 38 which is made sufficiently large to prevent the accumulation of large quantities of liquid in said trough. A screen 39 spaced slightly above the floor of the trough 36 traps any broken fibers that may be formed during the spinning operation and keeps them from flowing into the discharge conduit 38. The screen 39 also holds back the strand 26 which emerges from the outlet funnel 37 when starting up the apparatus, permitting the operator to string up the said strand without having to remove any of the strand from the trough 36 during the start up period. The trough 36 is provided with a removable cover 41 and is connected to an exhaust conduit 42 through which any gases or fumes that are liberated during the spinning operation may be drawn off.

As is shown more clearly in Fig. 4, the inlet funnel 27 is provided with radially extending wings 43 and is seated slidably in a collar 44 extending upwardly through the floor of the trough 24. One of the wings 43 is provided with a groove 45 in the face thereof which groove is adapted to receive a pin 46 projecting from the collar 44.

When the pin 46 is contained within the groove 45, the inlet funnel 27 is held in elevated position at a point spaced only slightly below the spinning jet 23. In this position, the flow of the coagulating medium into the inlet funnel 27 and through the spinning tube 28 will carry the strand 26 into and through said tube. Once the strand 26 has been threaded through the tube 28, the inlet funnel 27 may be returned to its normal spinning position, as shown in Fig. 2 of the drawings, in which it is spaced further away from the spinning jet 23 than at the start of the spinning operation. This mode of starting the spinning operation eliminates the necessity for wiping the face of the spinning jet 23 during the starting period and thereby reduces the amount of labor involved in said start up.

After emerging from the outlet funnel 37, the strand 26 passes over a two-finger guide 46', which wipes away a portion of the coagulating medium adhering thereto, and then through a slot 47 in the cover 41 to a godet wheel, indicated generally by reference numeral 48. The strands 26 from three spinning jets 23 are joined on the godet wheel 48 to form a tow 49 which is led from the godet wheel 48 over a guide pin 51 which is positioned at a level higher than said godet wheel. Any desired number of spinning jets 23 and godet wheels 48 may be included in the spinning section of the apparatus, and a tow 49 leaving any one of the godet wheels will ride over the pins 51 without coming into contact with any other of the godet wheels.

The tensions to which the filaments in the strands 26 are subjected in their passage from the spinning jet 23 to the godet wheel 48 may be closely controlled, to produce products having the most desirable physical properties, by regulating the velocity of the viscose composition through the said spinning jets, the spacing between the spinning jet 23 and the inlet funnel 27, the velocity with which the coagulating medium flows through the spinning tube 28 which can be altered by changing the effective liquid head under which said medium flows through said spinning tube and/or the diameter of said spinning tube, and the speed of the godet wheel 48. The two-finger guide 46' may also be adjusted to produce a desirable small additional tension between the said guide and the godet wheel 48. Under normal operating conditions, the filaments travel faster than the coagulating medium immediately after emerging from the spinning jet 23, then the coagulating medium travels faster than the filaments as it flows into and through the first portion of the spinning tube 28, and finally the coagulating medium travels at the same rate as or somewhat slower than the filaments as it flows through the last portion of the spinning tube.

In addition to permitting close control of all the conditions under which the strand 26 is produced, the spinning section of the apparatus of this invention provides a long bath travel in a very small space horizontally which brings the spinnerette 23 and the godet wheel 48 into such close proximity that stringing up by a single operator is extremely simple. The spinning section is also self-threading from the spinnerette 23 through the spinning tube 28 and is free from moving guides or rollers so that its construction and maintenance is simplified. The spinning jets 23 are effectively separated one from the other so that fresh coagulating medium is brought to the filaments emerging from each of said jets without having been contaminated or its concentration changed by contact with viscose from any other jet. Moreover, the filaments from one jet cannot interfere in any way with those of other jets either during start up or when there is a breakdown.

In producing a strand containing a large number of individual filaments, it is important to provide an adequate flow of coagulating medium to each of the filaments as it emerges from the spinning jet 23 to insure that each of the filaments is treated in the same manner and that the gases liberated from the viscose composition are swept away from the vicinity of the spinning jet. If an adequate

flow of coagulating medium is not provided, a sufficient quantity of the gases liberated from the viscose composition may accumulate on the lower face of the spinnerette to form bubbles which may interrupt the continuity of spinning of one or more filaments, particularly, where as here, the filaments are spun downwardly from the lower face of the spinnerette. In application Serial No. 224,353, filed May 3, 1951, of Russell O. Denyes, now U. S. Patent No. 2,673,368, dated March 13, 1954, there are disclosed spinnerettes that are specially adapted to be used in the apparatus of the present invention and will insure an adequate flow of coagulating medium to the filaments emerging from each of the apertures in the spinnerette.

Since the solutions employed and produced during the manufacture of the viscose fibers are corrosive, the several parts of the apparatus employed for handling the same are made of or coated with corrosion resistant material such as hard rubber, plastics, ceramics, lead, stainless steel and the like depending upon the use to which each part is put and the mechanical strength required thereof.

It is to be understood that the foregoing detailed description is given merely by way of illustration and that many variations may be made therein without departing from the spirit of my invention.

Having described my invention, what I desire to secure by Letters Patent is:

1. An apparatus for the production of filamentary materials comprising a trough for holding a coagulating medium, a second trough contiguous to said first trough, a channel communicating with said troughs for conducting overflow coagulating medium from said first trough to said second trough, a spinning jet positioned in said first trough for extruding a filament-forming composition into said coagulating medium in the form of filamentary materials, and a generally U-shaped spinning tube extending from said first trough to said second trough for carrying the filamentary materials and coagulating medium from said first trough to said second trough.

2. An apparatus for the production of filamentary materials, comprising a longitudinally extending trough for holding a coagulating medium, a second trough contiguous and parallel to said first trough, a channel between and communicating with said troughs for conducting overflow coagulating medium from said first trough to said second trough, a plurality of spinning jets in said first trough for extruding a filament-forming composition into said coagulating medium in the form of filamentary materials, and a plurality of generally U-shaped spinning tubes extending from said first trough to said second trough for carrying filamentary materials and coagulating medium from said first trough to said second trough.

3. An apparatus for the production of filamentary materials, comprising a trough for holding a coagulating medium, a spinning jet positioned in said trough for extruding a filament-forming composition into said coagulating medium in the form of filamentary materials, a spinning tube extending away from said trough for carrying the filamentary materials and the coagulating medium away from said trough, a movable inlet funnel cooperating with said spinning tube, and means for holding said inlet funnel in raised position so as to reduce the distance between the spinning jet and the inlet funnel at the start of the spinning operation to assist in guiding the filamentary materials through the spinning tube and in reducing the wiping of the spinning jet required at the start of the spinning operation.

4. An apparatus for the production of filamentary materials, comprising a trough for holding a coagulating medium, a spinning jet positioned in said trough for extruding a filament-forming composition into said coagulating medium in the form of filamentary materials, a second trough, a generally U-shaped spinning tube extending from said first trough to said second trough for carrying the filamentary materials and the coagulating medium from the first trough to the second trough, a movable inlet funnel

cooperating with said spinning tube, and means for holding said inlet funnel in raised position so as to reduce the distance between the spinning jet and the inlet funnel at the start of the spinning operation to assist in guiding the filamentary materials through the spinning tube and in reducing the wiping of the spinning jet required at the start of the spinning operation.

5. An apparatus for the production of filamentary materials, comprising a trough for holding a coagulating medium, a spinning jet facing downwardly positioned in said trough for extruding a filament-forming composition vertically downward into said coagulating medium in the form of filamentary materials, a second trough positioned adjacent to said first trough, a generally U-shaped spinning tube having its legs positioned vertically upward and having one leg positioned beneath said spinning jet, said tube extending from said first trough to said second trough for carrying the filamentary materials and the coagulating medium from said first trough to said second trough, an inlet funnel for guiding the filamentary materials and the coagulating medium into the leg of the spinning tube positioned beneath said spinning jet, said inlet funnel being moveable to reduce the distance between the spinning jet and the entrance to said inlet funnel at the start of the spinning operation to assist in guiding the filamentary materials through the spinning tube and in reducing the wiping of the spinning jet required at the start of the spinning operation, guides positioned in the spinning tube for guiding the filamentary materials along the center line of the

spinning tube to minimize the development of turbulence in the spinning tube, a discharge funnel for guiding the fibers and the coagulating medium out of the spinning tube, said discharge funnel increasing in cross-sectional area toward the outlet end thereof whereby the velocity of the coagulating medium flowing therethrough will decrease toward the outlet end thereof and the coagulating medium will not spurt from the outlet end of said funnel, and an overflow from said first trough to said second trough for maintaining a constant head of coagulating medium in said first trough on the inlet funnel.
